UNITED STATES PATENT OFFICE.

DAVID B. EBERLY, OF PINE VILLAGE, INDIANA.

IMPROVEMENT IN CULTIVATORS.

Specification forming part of Letters Patent No. 145,636, dated December 16, 1873; application filed May 31, 1873.

To all whom it may concern:

Be it known that I, DAVID B. EBERLY, of Pine Village, in the county of Warren and State of Indiana, have invented a new and valuable Improvement in Cultivators; and I do hereby declare that the following is a full, clear, and exact description of the construction and operation of the same, reference being had to the annexed drawings, making a part of this specification, and to the letters and figures of reference marked thereon.

Figure 1 of the drawings is a representation of my improved harrow and corn-cultivator by a plan view. Fig. 2 is a central section of the same. Fig. 3 is an elevation, and Fig. 4 a plan view, of a plow-beam and shovel used in combination with my cultivator; and Fig. 5 is a detailed view of one of the parts.

My invention relates to cultivators; and it consists of an expansible axle-tree, to which a various number of adjustable beams with harrow-teeth, cultivator, or plowshares may be attached, and in combination of a drag-beam, shovel - plow, and adjustable weed - cutting blade, as hereinafter described.

In the drawings, A represents a wheel, two of which are requisite to support my machine on a metallic axle, B, which is composed of a number of slotted pieces, b. The pieces b, at the right and left ends, are united with the axle-bearings of the wheels A, and the several pieces are very firmly fastened and clamped together by bolts, and with the aid of the adjustable fulcrums C, to which the plow-beams D are pivoted. The plow or cultivator shanks E are pivoted to the beams D by bolts d, and kept in position by segmental rods F, which are fastened to the sides of the plow-beams by hooked clamp-bolts f, the heads of which are pivoted to the shanks E by loose rivets e. Between two parallel braces, G, which are fastened to the axle-tree B, a roller, H, is pivoted, which, by a number of chains, d', holds the beams D suspended, and, by turning a handle, g, on the roller, the beams may be elevated considerably from the ground, and they may be secured in that position by slipping the drop-hook I over the corner of the roller. If it is desirable to pass one or the other plow over certain irregularities in the ground, or in the growth, or in the furrows, I provide the beams

of such plows with handles D¹, which I fasten to the sides of the beams, and steady them with braces d''. At the center of the axle-tree an arch, J, is attached, which carries near its top the hounds K, fastened together by the cross-bar L, steadied with the ends of the axle-tree B by diagonal braces M, and fastened to the axle by hooked clamp-bolts j; and there is also a spare hole for each bolt, in case the hounds should want to be fastened with a different inclination. The tongue is attached to the bolt N at the front ends of the hounds. The teams are attached to the draw-bars p, which are attached to the levers P, with their fulcrums p' fastened to the axle-tree B by means of the pin Z. The levers P are double-armed, and are connected, by rods o, to an equalizing-lever, O, fastened by a bolt, t, to the cross-bar L. The draw-bars p are held in a horizontal position by being passed through the eyes of two suspended rods, q, which are fastened to a cross-bar, Q, on the hounds K. The cross-bar Q is secured to the hounds K by clasps k. I hereby avoid a one-sided strain on my machine, which would be the result of applying the draft to the tongue, as is usually done, because the arch J would have to transfer all the power to the axle-tree, and for that purpose would have to be unusually strong and heavy to prevent it from bending or working with jerks, like a spring.

In working with plows I use the same mode of attachment and adjustment as with the cultivators, with two exceptions. The first difference consists in the use of one plow-beam for two plow-stands and two plow-shovels, and the mode of fastening the shovels with sockets S and set-screws s to the ends of the plow-stands E. The other difference exists at the end of the plow-beam, as represented by Figs. 3 and 4; the junction with the axle-tree being effected by two vertical laps, d², fastened to the end of the plow-beam D, embracing a pivot-head, d³, to which they are pivoted, the said pivot-head forming a part of the horizontal clamp-plate D², which is inserted between the slot of the middle link, b, of the axle-tree, and for the purpose of which the said middle link is provided with two lugs, b', between which the clamp-plate D² is fastened by a bolt. The mode of attaching the shovels with sockets en-

ables the operator to construct the shovels with two working ends, so that they may be reversed, like the shovel R'. (Seen in Figs. 3 and 4.)

The axle-tree B may be made long or short by adding or removing as many of the slotted links b as are necessary for the purpose, the middle link retaining its place, for the sake of its peculiar construction and purpose, except when corn-rows are to be cultivated with a tolerably high growth of corn, in which case it is removed, so that the open arch J may pass over the corn without injuring it. The slotted links b may be overlapped more or less, to allow the fastening and arrangement of the bearings C at any desirable distances. It must, of course, be understood that, if the roller H is to be used, the length of the axle-tree must be corresponding.

In case of obstructions by very tough and tangled weeds, I make use of a knife-blade, T, which is fastened to the plow-beam D, and may be adjusted so as to enter the ground when it is necessary to cut any roots. The plow-beams D, in Figs. 3 and 4, are provided with eyebolts u, for the purpose of suspending them on the hooks U, fastened to the hounds K, when the machine is to be moved without plowing.

Fig. 5 shows one of the weed-cutting knives, the adjustability of it consisting in a bolt-hole, t, serving as fulcrum, and a slot, t', serving as adjustable means for fastening.

What I claim as new, and desire to secure by Letters Patent, is—

1. The expandible axle-tree B, consisting of the slotted links b, substantially as specified.
2. The combination, with a drag-beam, D, of the shovel-plow and the adjustable weed-cutting knife-blade attached to the sides of said drag-beam, and extending rearwardly of the share, as shown, and for the purpose mentioned.
3. In a cultivator, the detachable middle slotted link b, in combination with the arch J, substantially as specified.
4. The fulcrum p', with its connection-pin Z, in combination with the slotted extension-axle B, substantially as specified.

In testimony that I claim the above I have hereunto subscribed my name in the presence of two witnesses.

DAVID B. EBERLY.
